[57] CLAIM

The ornamental design for a partition-mountable writing instrument holder, as shown and described.

DESCRIPTION

FIG. 1 is a perspective view of a partition-mountable writing instrument holder showing our new design;

FIG. 2 is a rear elevational view;

FIG. 3 is a left side elevational view, the right side being a mirror image thereof; and

FIG. 4 is a top plan view thereof.

FIG. 1

FIG. 2

FIG. 3

FIG. 4
